United States Patent Office

Des. 208,369
Patented Aug. 22, 1967

208,369

CIGARETTE LIGHTER

Seymour Rappoport, Rumson, N.J., assignor to Ronson Corporation, Woodbridge, N.J., a corporation of New Jersey

Filed Sept. 8, 1966, Ser. No. 3,774

Term of patent 14 years

(Cl. D48—27)

Fig. 1.

Fig. 2.

Fig. 3.

Fig. 4

Fig. 5.

FIG. 6.

FIG. 7.

FIG. 8.

FIG. 1 is a side and end perspective view of a cigarette lighter showing my new design.

FIG. 2 is a view showing the lighter removed from the base.

FIG. 3 is a top plan view.

FIG. 4 is a side view thereof with the base shown in cross section.

FIG. 5 is a view of the opposite side of FIG. 4 with the base shown in cross section.

FIG. 6 shows the other side of the lighter depicted in FIG. 3 with the base removed.

FIG. 7 is a front end view thereof with the base shown in cross section.

FIG. 8 is a rear end view thereof with the base shown in cross section.

I claim:

The ornamental design for a cigarette lighter, substantially as shown and described.
